INFANT'S CRADLE CHAIR

Emil J. Carlson and Clarence G. Carlson, Oakland, Calif.

Application July 7, 1955, Serial No. 36,859

Term of patent 14 years

(Cl. D5—5)

Fig. 1.

Fig. 5.

Fig. 2.

Fig. 6.

Fig. 4.

Fig. 1 is a perspective view, viewed from the side and above, of an infant's cradle chair showing our new design;

Fig. 2 is a top plan view thereof;

Fig. 3 is a side elevational view thereof;

Fig. 4 is a perspective view, viewed from the side and below, thereof;

Fig. 5 is a rear elevational view thereof; and

Fig. 6 is a front elevational view thereof.

We claim:

The ornamental design for an infant's cradle chair, as shown.
